FRAME CONSTRUCTION FOR DOORS OR
WINDOWS

Nore Andersson, Goteborg, Sweden, assignor to
Aktieboleget Götaverken, Goteborg, Sweden, a
corporation of Sweden

Application June 22, 1938, Serial No. 215,091
In Sweden November 5, 1936

4 Claims. (Cl. 189—69)

The present invention relates to improvements in frame constructions for doors or windows, i. e. in the construction of sash frames or fixed door or window frames. One object of the invention is to provide a frame construction, in which the sections forming the frame are of simple shape and may be manufactured at low cost, and in which the frame has small weight. A further object is to provide a sash frame in which a glass plate may be fitted in a simple and efficient manner. The frame construction according to the invention, which comprises L-shaped metal sections, is principally characterized in that the frame members comprise open L-shaped sheet metal sections having one leg of the L disposed perpendicularly to the door or window plane and the other leg directed towards the space between a sash frame and an adjacent sash frame or an adjacent door or window frame cooperating therewith, the sheet metal of said other leg being bent over at least 180° at the free longitudinal edge of said leg and adapted to cooperate at said bent and thereby strengthened portion of said other leg of the open L-shaped sheet metal section with said adjacent frame, preferably through the intermediation of a packing.

The above mentioned and other objects and features of the invention are further disclosed in the following description of some embodiments of the invention illustrated by way of example on the accompanying drawings, in which:

Fig. 1 is a perspective front view of a window according to the invention, Fig. 2 a section on line II—II in Fig. 1, and Fig. 3 a section on line III—III in Fig. 1. Fig. 4 is a front elevation of an espagnolette and Fig. 5 is a side view of the lower end of said espagnolette. Figs. 6 and 7 are cross sections illustrating modifications of the frame sections used in the frame construction illustrated in Figs. 1-3.

In Figs. 1-3 1 designates a wall having a stationary frame provided therein. The stationary frame comprises a small sheet metal section 2, 3 at the inner side of the window and a substantially L-shaped sheet metal section 4, 5, which is heat insulated relatively to the first mentioned section 2, 3. The two sections are separated by a layer 6, which may consist of heat insulating material. One leg 4 of the L-shaped section is bent at 7 to form together with the leg 3 of the other section a groove, in which a packing 8 of rubber, felt or the like is disposed. The free end of the other leg 5 is double folded and forms a rib 9 directed towards the leg 4 and forming together with the leg 5 a channel opening towards

the leg 4. At the inner side of the leg 3 of each vertical frame section 2, 3 a recess 10 is provided in the wall to accommodate one part 11 of a hinge 11, 12 extending through a suitable opening in the leg 2 of the sheet metal section 2, 3. The part 11 is spot welded to the leg 3. However, it may naturally be riveted or bolted thereto, if desired.

The movable window frame or sash comprises substantially L-shaped sheet metal sections 13, 14 and 15, 16 and band-shaped sheet metal sections 17 and 18 provided with grooves for packings 8. The legs 13 and 15 of the L-shaped sections, which are parallel to the window plane, are bent over or double folded at their free ends in similar manner as the legs 5 of the stationary frame sections 4, 5 so that ribs 19 and 20, respectively, directed towards the interior of the respective frame section are formed. The ribs 9, 19 and 20 of the stationary frame sections and the sash sections, respectively, are adapted to cooperate with the packings 8. The part 12 of each hinge 11, 12 is inserted through the leg 13 of the vertical section 13, 14 and secured to said section through spot welding or in any other suitable manner. The legs 13 consequently show a completely smooth surface at the inner side of the window and the hinge parts 12 are substantially concealed in the interior of the sections. The legs 14 and 16 are folded some 180° at 21 and 22, respectively, forming a fold extending along the frame and producing one wall of a seat necessary for fitting the glass plate. The glass plates 24 are fitted between said fold and strips 23 and their edges are embedded in packings 25. Also the band-shaped sheet metal sections 17 and 18 are multiple folded so as to form folds 26 and 27, respectively, between which and strips 23 secured to the sections the glass plates 24 and their packings 25 are secured. The strips 23 may be secured to the sections by means of spot welding. The frame sections 13, 14 and 17 forming the vertical side members of the window sash are connected by means of hinges 23. The central vertical sections 13, 14 and 17, and 15, 16 and 18, respectively, are connected to each other by means of clasping means 29 of any suitable type. The space between the sections 15, 16, 18 of the left window in Fig. 3 and the sections 13, 14, 17 of the right window may preferably be utilized for accommodating espagnolettes or other means necessary for operating the window. In Fig. 3 locking rods 30 are provided in the interior of the leg 13 of the central vertical section of the inner right window. Each rod 30 is provided with a

toothed rack 31 at one end, which cooperates with a gear 32 provided on a shaft 33 of the operating handle 34, as illustrated in Figs. 3 and 4. At the upper and lower ends of the rods 30 fingers 35 are provided, as illustrated in Figs. 2, 4 and 5, which may engage pins 36 provided on brackets 37 welded to the stationary frame. Drip plates 38 are welded to the lower sash members 17 of the outer windows.

In the above described coupled double window the inner and outer surfaces of the window frame sections are smooth and of simple shape, and the hinges, espagnolettes or the like are substantially concealed in the interior of the frames. The above described frames may be made from sections forming the inner frame as well as the outer frame of a door or window, and said frames may be divided in the door or window plane, for instance after securing the hinges or other connecting means so that the inner and outer frames may be swung apart. Thus, the sections 13, 14 and 17, and 15, 16 and 18, respectively, may before the division in the window plane be connected at their adjacent edges.

The above described frame construction according to the invention may naturally be modified in several different ways, and the invention may, for instance, also be applied to plain or single doors or windows. The folding, bending or the like of the sheet material of the sections for forming the fold or seat for the glass plate may be carried out in different ways. The 180° folding or bending of the sections may, for instance, comprise an arcuate bend, or two 90° bends, as illustrated at 21 and 22 in Figs. 2 and 3, or one 180° bend, as illustrated at 39 and 40 in Fig. 6, which shows a modified frame section according to the invention. In this case the frame section 41, 42 is connected to the outer frame section 43 by means of a hinge 28 in the same way as the sections 13, 14 and 17 in Fig. 3. The 180° fold 40 is continued by a further fold 44 between which and strips 23 the glass plate 24 and its packing 25 are secured in the manner above described. The leg 41 is triple folded at 45 to make the section more rigid. Fig. 7 illustrates a further embodiment of the invention, in which the band-shaped section 46 is provided with a 180° arcuate fold 47 forming a seat for the glass plate 24 and its packing 25 between which and the free edge of the fold 47 a suitable strip of soft material 48 may be provided. The L-shaped section 49, 50 is folded substantially in the same way as the sections 13, 14 and 15, 16 in Fig. 3 but the legs 46 and 50 of the two sections may in this case be folded twice at 51 and 52 to form the inner walls of the seat for the glass plates 24 so that the strips 23 or putty strips or the like may be dispensed with. The sections 46 and 49, 50 may be connected by a hinge 53. Obviously the folds 39 and 40 or 21, 22, 26, 27 may have the same arcuate shape as the fold 47.

It is to be understood that the embodiments of my invention hereinabove described have

been given merely by way of illustration and do not constitute a limitation of the scope of my invention, which is to be determined by the appended claims.

5. What I claim is:

1. A door or window structure including hinged and fixed frames, at least one of the frames being of sheet metal having an L-shaped cross-section with one leg of the L disposed perpendicular to the door or window plane and the other leg directed towards the adjacent frame member cooperating therewith, the sheet metal of said other leg being bent over at least 180° at the free longitudinal edge of said leg and directly cooperating at said bent and thus strengthened edge portion with a portion of said adjacent frame member.

2. A door or window structure including hinged and fixed frames, at least one of the frames being 20 of sheet metal having an L-shaped cross-section with one leg of the L disposed perpendicular to the door or window plane and the other leg directed towards the adjacent frame member cooperating therewith, the sheet metal of said other leg being bent over at least 180° towards the interior of the L-section at the free longitudinal edge of said leg and directly cooperating at said bent and thus strengthened edge portion with a portion of said adjacent frame member.

3. A door or window structure including hinged and fixed frames, at least a hinged frame of which is of sheet metal having an L-shaped cross-section with one leg of the L disposed perpendicular to the door or window plane and providing a fold formed by two spaced 90° bends in opposite directions of the sheet material of said leg adjacent the corner of the L-shaped section, which fold extends in the door or window plane towards the door or window opening and forms 40 a flange against which a glass plate is held, and having another leg directed towards the adjacent frame member cooperating therewith, the sheet metal of said other leg being bent over at least 180° at the free longitudinal edge of said leg and directly cooperating at said bent and thus strengthened edge portion with a portion of said adjacent frame member.

4. A door or window structure including 50 hinged and fixed frames, at least a hinged frame of which is of sheet metal having an L-shaped cross section with one leg of the L disposed perpendicular to the door or window plane and providing a groove formed by an U-shaped depression of the sheet material of said leg adjacent the corner of the L-shaped section, which groove opens towards the door or window opening and extends around said opening and forms a seat for a glass plate, and having another leg directed towards the adjacent frame member cooperating therewith, the sheet metal of said other leg being bent over at least 180° at the free longitudinal edge of said leg and directly cooperating at said bent and thus strengthened portion with a portion of said adjacent frame member.

NORE ANDERSSON.
